[57] CLAIM

The ornamental design for a wall clip, shown and described.

DESCRIPTION

FIG. 1 is a front perspective view of a wall clip showing my new design;

FIG. 2 is a front elevational view thereof;

FIG. 3 is a right side elevational view thereof, the left side elevational view being a mirror thereof;

FIG. 4 is a bottom plan view thereof, the broken line showing of the adhesive strip or magnetic strip is for illustrative purposes only and forms no part of the claimed design;

FIG. 5 is a top plan view thereof; and,

FIG. 6 is a rear elevational view thereof.
